(57) **CLAIM**

The ornamental design for a machining sample of machine tools, as shown and described.

DESCRIPTION

FIG. 1 is a front perspective view of a machining sample of machine tools showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom view thereof.

1 Claim, 5 Drawing Sheets

FIG. 2

FIG. 3**FIG. 4****FIG. 5****FIG. 6**

FIG. 7

FIG. 8
